UNITED STATES PATENT OFFICE.

OTTO M. KNOBLOCK, OF SOUTH BEND, INDIANA.

DESIGN FOR A DEMAGNETIZER.

SPECIFICATION forming part of Design No. 34,015, dated January 29, 1901.

Application filed January 7, 1901. Serial No. 42,452. Term of patent 7 years.

To all whom it may concern:

Be it known that I, OTTO M. KNOBLOCK, a citizen of the United States, residing at South Bend, in the county of St. Joseph and State of Indiana, have invented and produced a new and original Design for Demagnetizers; and I do declare the following to be full, clear, and exact description of the same, reference being had to the accompanying sheet of drawings, forming a part thereof, in which my new and original design for demagnetizers is shown in perspective.

As shown in the drawing, the leading or material feature of my design for demagnetizers consists of a rectangular base or support having mounted thereon a substantially oval-shaped demagnetizing-chamber.

Referring to the drawing, the letter A represents the rectangular base or support, the four corners of which are rounded, as at a.

b, c, and d represent, respectively, a binding-post, spring-switch, and contact-point, which are on the upper surface of the said base or support A and near one end thereof.

25 B represents the two oval-shaped holders,

convexed, as shown, and C represents the curved supporting-legs terminating in the rectangular-shaped feet D.

E represents the oval-shaped demagnetizing-chamber, made from coiled wire.

30 From the foregoing description it will be observed that my new and original design consists of the rectangular base or support provided with rounded corners, the oval-shaped convexed holders or plates provided with the 35 supporting legs and feet, and the oval-shaped demagnetizing-chamber.

Having thus described my invention, what I claim as new, and desire to secure by Letters Patent, is—

40 The design for a demagnetizer, substantially as herein shown and described.

In testimony whereof I have signed my name to this specification in the presence of two subscribing witnesses.

OTTO M. KNOBLOCK.
